(57) **CLAIM**

The ornamental design for a motor vehicle accessory, as shown and described.

DESCRIPTION

FIG. 1 is a front view of my ornamental design for a motor vehicle accessory.

FIG. 2 is a rear view thereof.

FIG. 3 is a top plan view thereof.

FIG. 4 is a bottom plan view thereof.

FIG. 5 is a right side elevational view thereof.

FIG. 6 is a left side elevational view thereof.

FIG. 7 is a perspective view thereof.

FIG. 8 is a front view of a first alternative embodiment of my ornamental design for a motor vehicle accessory.

FIG. 9 is a rear view of the embodiment of FIG. 8.

FIG. 10 is a top plan view of the embodiment of FIG. 8.

FIG. 11 is a bottom plan view of the embodiment of FIG. 8.

FIG. 12 is a right side elevational view of the embodiment of FIG. 8.

FIG. 13 is a left side elevational view of the embodiment of FIG. 8.

FIG. 14 is a perspective view of the embodiment of FIG. 8.

FIG. 15 is a front view of a second alternative embodiment of my ornamental design for a motor vehicle accessory.

FIG. 16 is a rear view of the embodiment of FIG. 15.

FIG. 17 is a top plan view of the embodiment of FIG. 15.

FIG. 18 is a bottom plan view of the embodiment of FIG. 15.

FIG. 19 is a right side elevational view of the embodiment of FIG. 15.

FIG. 20 is a left side elevational view of the embodiment of FIG. 15; and,

FIG. 21 is a perspective view of the embodiment of FIG. 15.

The structures shown in phantom or broken lines in FIGS. 1-21 form no part of the claimed design and are included only to illustrate an environment.
